DETACHABLE SCROLL FOR PORTABLE DESKS

Filed Feb. 11, 1920

Fig. 2.

Inventor:

Lewis E. Myers

By: N. S. Anshutz
Attorney

UNITED STATES PATENT OFFICE.

LEWIS E. MYERS, OF VALPARAISO, INDIANA.

DETACHABLE SCROLL FOR PORTABLE DESKS.

Application filed February 11, 1920. Serial No. 357,840.

To all whom it may concern:

Be it known that I, LEWIS E. MYERS, citizen of the United States, residing at Valparaiso, in the county of Porter and State 5 of Indiana, have invented certain new and useful Improvements in Detachable Scrolls for Portable Desks, of which the following is a specification.

My invention relates to improvements in 10 detachable scrolls for portable desks and it consists more especially of the features hereinafter pointed out in the annexed claims.

The purpose of this invention is to provide means whereby portable or other desks 15 may be supplied with interchangeable topical scrolls, so as to increase their scope of educational and recreative usefulness; that makes provision for different positioned and variable-sized display areas; that retains the 20 use of a pivoted desk board in connection with the supporting frame, either in front or to the rear of the same; that provides means for display areas at an angle to the frame.

25 With these and other ends in view I illustrate in the accompanying drawing such instances of adaptation as will disclose the broad underlying features without limiting myself to the specific details shown.

30 Fig. 1 is a side elevation partly in section of a desk frame and accessories.

Fig. 2 is a plan view of one edge of the frame.

35 Fig. 3 is a detached plan of the frame, extended bale, etc.

Fig. 4 is a perspective view of a bale retaining spring plate.

In carrying my invention into practice I employ two edge or side pieces 1. These 40 are joined together by an upper cross-piece 2, a lower one 3 and other intermediates 4 and 5. At the top on the rear side a hand-hole cross piece 6 is secured to the sides 1. These cross pieces determine the width of 45 the frame. The rear side of the frame is enclosed by a cover or backing 10 which may have a map or other study subject mounted thereon. Between the cross pieces 4 and 5 variously arranged compartments 50 may be placed as desired. The side pieces 1 may be made of greater relative length than shown in the drawing so as to provide a longer up-and-down display area in which case the side arms 16 of the supporting bale 55 15 would be lengthened accordingly.

In ordinary use desks of this type employ a swinging desk board 21 which may be a black board on one side and a drawing board on the other provided with side rails 22. The board 21 in its space between the 60 rails is slightly wider than the width of the main frame which allows the board to be swung up against the front of the frame to close it as the side rails overlap the parts 1. While in this position the board is held 65 by the bale 15 in position F with its short ends 17 in the openings 26 formed in the side rails 22 and spring plates 18 that enter grooves 23 of such rails. In its open or bale position G the board may engage front 70 notch 34 or the rear notch 35 accordingly as the board is supported by the bale 15, in position G at the front of the frame or in position H at the rear of the frame. While so positioned it may be locked by a suitable 75 bolt (not shown in detail) from the frame 1, which enters an opening in one of the side bars 22.

When interchangeable topical scrolls 33 are to be used in connection with the frame 80 it may be attached to a convenient place on the wall by means of ordinary screw hooks 14 which engage screw eyes 13 attached to the sides 1 of the frame, the board 21 is detached from the bale ends 17 and a transfer 85 or storage roller 28 having end extensions 30 and holes 31 is placed on the bale 16 so that the bale ends 17 enter holes 31. The bale itself may be held horizontal by notches 20 formed in spring plates 18 as the straight portion 90 27 of the bale snubs into them, or it may be held in position G when also detached from the board 21 by notches 25 in the spring projection 19. These plates are formed right and left hand, one for each upright 1. 95 They also form a bearing for the bale 15. At the point where these spring plates are located the uprights 1 are recessed under the spring portion of the plates so as to permit the spring ends to have in and out movement.

The permanent rollers 7, 8 and 9 are located in the frame, roller 7 is at the top, roller 9 at the bottom and roller 8 between the others. These rollers and the transfer 105 rollers 28 have slots to receive either end of interchangeable scrolls 33. The rollers 7, 8 and 9 are turned from the outside of the frame by knobs 12 that are connected to the rollers by reduced diameters where such 110

smaller diameters pass through holes in the uprights 1 (not shown). Heads 24 are placed on these rollers to retain scrolls 33 in correct endwise relation as they are wound on the rollers. The transfer rollers 28 have knurled heads 29 to locate the endwise position of the scrolls and free ends 30 in which central holes 31 are formed for the bale ends 17.

10 The free ends 30 facilitate the handling of the rollers 28, there being as many of these as there are separate subjects. On account of such ends the scrolls will not be so readily soiled, besides they serve to lengthen the 15 transfer rollers to meet the bearing ends 17 of the bale. In addition they also serve to support the rollers in suitable filing cases.

The transfer or storage rollers may be filed in specially constructed cabinets provided with retaining means for each roller but as such filing accessories do not form a part of the present invention they are not shown.

It will be noted from the drawing that 25 with the three relatively permanent rollers 7, 8 and 9 and one transfer roller 28 with a scroll 33, numerous combinations, in position and extent of the display portion of the scrolls, may be secured. A transfer scroll 33 on its roller 28 is placed on the bale ends 17 with its rear end on the outside. This end is placed in slot 32 of roller 8 and this roller is turned to unwind the scroll from roller 28. This gives, with the 30 bale in position E, a short inclined display portion B. After the scroll has been wound onto roller 8 its front end will be on the outside.

In the ordinary position of the scroll 40 with its contained data, on one or both sides it is run off from roller 8 onto roller 7 which gives the display area A. In order to make each scroll serve a double purpose it is printed on both sides, and for this reason the scrolls must be detachable as otherwise it will be impossible to use both sides. This relation will be readily understood by reference to the drawing in which a scroll is shown fully wound on roller 8 with one 45 display face standing to the right hand side of Fig. 1. As the contents of roller 8 are wound onto roller 7 in the direction of the arrow, or anti-clock wise, the last end of the scroll is then passed through the upper slot 50 11 and then across the back 10 to the lower slot 11 onto roller 9, where it is wound as needed. In this way the reverse side of the scroll is brought to view for study or otherwise. Should the scroll be first wound onto 55 roller 7 then its front end can be passed through upper and lower slots 11, formed in the backing 10 and then onto the lower roller 9. In this relation the display area D will be of considerably larger extent 60 than that contained in A admitting of com-

parative study of sequential data. If the scroll roller 28 and the bale arms 16 are in the position G and the scroll is wound onto the upper roller 7 a long diagonal display area C is produced which may be 70 modified in angle and extent by using roller 8 instead of 7. When scrolls are to be taken off and stored or filed they are so manipulated that the rear end of the scroll is found on the outside when the transfer 75 roller is filled. Sub titles may be printed on this end to facilitate the filing and use of these unique educational aids.

Without going into a lengthy schedule of uses to which this educational device can 80 be put it is sufficient to say that it has almost unlimited possibilities of expansion, its flexibility lends itself to all kinds of adaptations, history, mathematics, music, chemistry, forestry, agriculture, electricity, 85 mechanics, physics, architecture, physiology, domestic science, astronomy, etc., may be brought within the reach of the student for study and recreation. The presentation of study subjects in this manner places in the 90 hands of the child as well as the grown person an instrument of self-help which in its practical application is universal in its adaptations.

What I claim is,

1. In interchangeable scroll display devices, a plurality of rollers, removable scrolls attachable to and detachable from the rollers at will, a suitable frame on which said rollers are supported, and a supplementary pivoted roller support adapted to hold a transfer roller in substantial parallelism with the other rollers at various distances therefrom.

2. In desks, a suitable frame, a plurality of rollers supported thereby, a swinging bale also supported by the frame, a removable roller held between the free ends of the bale, and means for retaining the side arms of the bale in different angular positions with respect to the frame.

3. In desks, a suitable frame, a plurality of rollers, having bearing in the frame, a pivoted bale also supported by the frame, side arm projections from the bale, said arms terminating in the frame, means for pivoting the bale in bearing ends, means for supporting the bale in different positions, a board pivoted on the bearing ends of the bale, a separate and interchangeable transfer roller, the board or the roller being adapted to function on the bearing ends of the bale.

4. In educational devices, a suitable frame, an upper roller, a lower roller, an intermediate roller, a backing to the frame having slotted openings through the same adjacent the upper and lower rollers to leave the backing unbroken between said openings, slots in the rollers, and attachable and de-

tachable scrolls adapted to be placed on the rollers as desired so as to exhibit the scroll with equal facility either on the backing or in front of the upper and intermediate 5 rollers.

5. In educational devices, a suitable frame having side top and bottom members, a backing placed on the frame leaving the sides and front open, a plurality of rollers supported in the sides in parallel relation to each other, a roller being placed adjacent each of the top and bottom edges of said backing and in front of the same, and a scroll attachable to and removable from 10 the rollers adapted for display in front of the rollers as it is stretched between two of them and also adapted to be displayed 15 with equal facility on the backing while held by two rollers.

20 6. In desks, a suitable frame, a plurality of relatively permanent rollers supported by

the frame, a separate adjustable support, a transfer roller on the same, an interchangeable scroll on the transfer roller, and means for removing the scroll to the other rollers 25 in any desired order and direction through the insertion of the scroll in the slots of one of the permanent rollers and thereafter actuating such roller.

7. An educational device, comprising a 30 frame adapted for display purposes on its front and rear, a backing on the rear, a plurality of rollers supported by the frame in front of the backing, a detachable scroll, means for detachably securing the same to 35 said rollers for similar area display on the front or rear of the frame with equal facility.

In testimony whereof I affix my signature.

LEWIS E. MYERS.
